(57) **CLAIM**

The ornamental design for a speakerphone, as shown and described.

DESCRIPTION

FIG. 1 is a top perspective view of a speakerphone, showing our new design;

FIG. 2 is a top plan view thereof;

FIG. 3 is a bottom plan view thereof;

FIG. 4 is a right side view thereof;

FIG. 5 is a left side view thereof;

FIG. 6 is a front view thereof; and,

FIG. 7 is a rear view thereof.

The broken line portions of FIGS. 1-6 are included to show unclaimed subject matter only and form no part of the claimed design.

1 Claim, 7 Drawing Sheets

FIG. 1

FIG. 2

FIG. 3

FIG. 4

FIG. 5

FIG. 6

FIG. 7
